[57] CLAIM

The ornamental design for a telephone index, as shown and described.

DESCRIPTION

FIG. 1 is a perspective view of a telephone index showing my new design with the drawer in the closed position;

FIG. 2 is a perspective view as in FIG. 1 but with the drawer in the open position;

FIG. 3 is a top plan view thereof with the drawer closed;

FIG. 4 is a front elevational view thereof;

FIG. 5 is a rear elevational view thereof;

FIG. 6 is a right side elevational view thereof; and

FIG. 7 is a bottom plan view thereof.
